UNITED STATES PATENT OFFICE

149,777

DESIGN FOR A LINGERIE CHAIN

Opal E. Scarborough, Dallas, Tex.

Application August 9, 1946, Serial No. 132,375

Term of patent 7 years

(Cl. D17—3)

To all whom it may concern:

Be it known that I, Opal E. Scarborough, a citizen of the United States, residing at Dallas, in the county of Dallas and State of Texas, have invented a new, original, and ornamental Design for a Lingerie Chain, of which the following is a specification, reference being had to the accompanying drawing, forming part thereof.

The figure of the drawing illustrates a lingerie chain showing my new design, in which the clasps are shown in perspective, plan and side elevational views, respectively.

I claim:

The ornamental design for a lingerie chain, substantially as shown.

OPAL E. SCARBOROUGH.
